SVEN JOHAN NORDSTROM, OF SAN FRANCISCO, CALIFORNIA, ASSIGNOR, BY DIRECT
AND MESNE ASSIGNMENTS, TO MERCO NORDSTROM VALVE COMPANY, OF SAN
FRANCISCO, CALIFORNIA, A CORPORATION OF DELAWARE.

VALVE FOR TANK CARS AND THE LIKE.

Application filed August 28, 1923. Serial No. 584,618.

To all whom it may concern:

Be it known that I, SVEN JOHAN NORDSTROM, a subject of the King of Sweden, and a resident of San Francisco, in the county of San Francisco and State of California, have invented certain new and useful Improvements in Valves for Tank Cars and the like, of which the following is a specification.

10. The invention relates to an improvement in valves for tank cars and the like.

The drainage valves of tank cars is located in the bottom of the tank and is provided with a stem which extends upwardly 15 through the tank and terminates in a handle within the dome. By reason of the flexibility of the tank and consequent buckling as the car rounds a curve and because of the impurities and foreign substances contained in the oil, gasoline or other lading 20 carried by the tank, great difficulty has hitherto been experienced in preventing the valves from leaking. In fact, so far as is known, no completely satisfactory valve has 25 yet been designed for tank car service. There are two types of tank car valves in common use. The first is a flat, circular disc which seats in a beveled circular hole in the bottom of the tank. As the contents of the 30 tank drain out, a portion of the dirt and other sediment contained therein lodges on the valve seat and when the valve is closed this prevents the valve from making a tight closure. Hence when the cap is removed 35 from the drainpipe projecting downwardly from the bottom of the tank, there is always a waste of oil, gasoline or other liquid.

The second common type of valve for tank car service is a plug valve specially adapted 40 for the purpose. These plug valves, as heretofore constructed, have been even more unsatisfactory for tank car service than disc valves, for the reason that it has been impossible to lubricate them until the contents 45 of the car have been drained off. This lack of lubrication results in the plug valve becoming stuck or "frozen" in its seat. When this occurs, the efforts to loosen the plug cause the contacting metal to strip and there- 50 after the valve leaks.

The arrangement of the valve parts in the bottom of the tank has heretofore proven unsatisfactory, because when the downwardly projecting drain pipe has encountered some

obstacle whereby it has been bent or broken, 55 the stress to which the pipe is subjected is usually sufficient to distort the bearing or seating surfaces of the valve, and this in spite of the fact that grooves have been provided in the drain pipe to cause it to break 60 easily without transmitting the strain to the valve.

One object of the present invention is to produce a tank car valve of the plug type 65 which may be readily lubricated while the valve is in place and while the tank is full of liquid. A further object of the invention is to produce a tank car valve which, when it is stuck or "frozen" to its seat, may be readily lifted therefrom by means 70 located in the dome at the top of the tank. Another object of the invention is to so arrange the valve parts in the bottom of the tank that any stress or shock to which the drain pipe is subjected will not be communicated to the bearing or seating surfaces of 75 the valve. Still further objects of the invention will be pointed out as the description proceeds. With these objects in view, the invention consists in the improved plug 80 valve for tank cars hereinafter described and particularly pointed out in the appended claims.

The preferred form of the invention is illustrated in the accompanying drawings, 85 in which Fig. 1 is a vertical section of a portion of a tank car showing the improved valve applied thereto; Fig. 2 is an enlarged sectional detail of the means for compressing the lubricant to lift the valve from its seat; Figs. 3 to 7 inclusive are enlarged detail views of the valve and associated parts shown in Fig. 1; Fig. 3 is a longitudinal section through the valve casing; Fig. 4 is a section of the upper part of the valve; Fig. 95 5 is a top plan, partly in section, of the valve; Fig. 6 is a section taken on the line 6-6 of Fig. 3; and Fig. 7 is a top plan of the valve and adjacent parts of the tank.

The improved tank car valve, as illustrated in Fig. 1, comprises a valve casing 12 located in the bottom of the tank 13, and a plug or valve proper 14 seated in a vertical, tapered bore in the valve casing. The casing is provided with an elbow-shaped passageway 15 therethrough, having an inlet 16 opening into the interior of the tank, and an outlet opening 17 which regis-

ters with the usual drain pipe 18. The open lower end of the drain pipe is closed by the cap 19. As usual, the upper end of the drain pipe 18 is provided with a circumferential groove 20 so that the pipe may break off without communicating the stress or shock to the valve parts. To prevent any possibility of the valve parts becoming strained by reason of damage to the drain pipe, the present invention contemplates a novel construction by which the valve parts are located in the bottom of the tank. To this end, a plate 22 is provided, having a smooth upper surface upon which the bottom of the valve casing 12 is adapted to rest. A gasket 23 is interposed between the two contacting surfaces to insure a tight joint. The valve casing is secured to the plate 22 by means of cap screws 24. It will be observed that the plate 22 is dish-shaped and that the bottom of the valve casing is inserted in the dished portion of the plate so that the bottom 26 of the hole 27 through the valve plug 14 and the bottom of the inlet opening 16 of the passageway through the valve casing are substantially flush or level with the bottom of the tank. Thus there is a complete drainage of the contents of the tank. The upper outwardly projecting flange 28 of the plate 22 is secured to the shell of the tank by means of rivets 29. This construction facilitates the caulking of the joint between the flange 28 and the shell of the tank. The flanged upper end 30 of the drain pipe 18 is secured by studs 31 to the thickened portion 32 of plate 22. It will be observed that the above described construction is such that even if the drain pipe 18 does not break at the groove 20, the shock or stress cannot be communicated to the bearing or seating surface of the valve.

The valve plug 14 is arranged to be turned through an angle of 90 degrees to open and close the valve. The plug is shown in the drawings in closed position. To manipulate the valve plug, a hollow stem or pipe 35 is provided extending from the plug up through the tank and terminating in the dome 34. The lower end of the stem 35 projects into the recess 36 formed in the upper end of the plug 14 and is bifurcated to loosely embrace the lugs 37 projecting radially into the recess 36. The upper end of the stem 35 is embraced by a head 38 which receives the inner end of the handle 39 by which the valve plug is manipulated: and the bolt 40 secures the handle 39 in the head 38. In order that the plug may be turned through an arc of only 90 degrees at each manipulation, a stop pin 42 is adapted to be engaged by the ends of the arcuate slots or grooves 43 formed in the upper surface of the plug. The pin 42 is secured in a plate 44 fastened to the upper

part 45 of the valve casing 12. The valve plug is yieldingly held against its seat by means of a flexible diaphragm 47 secured by the cap screws 48 to the valve casing. Interposed between the raised central portion 49 of the plug and the rim of the central opening in the diaphragm 47 is a series of washers 50. This construction permits the valve to be lifted from its seat to be lubricated, or in case it should be struck or frozen thereto, by the means to be presently described.

So far as is known, it has not been proposed heretofore to provide tank car valves of the plug type with means for lubricating them from the top of the tank. To facilitate the introduction of lubricant into the bearing surface of the valve, means located at the top of the tank are provided to lift the plug from its seat. The lifting of the plug may be accomplished by two means: (1) by fluid pressure; (2) by mechanical action. In the preferred form of the invention, the valve plug is lifted from its seat by fluid pressure. This is effected by utilizing the means for lubricating the valve. A chamber is provided between the valve plug and the casing and the lubricant is forced into the chamber and put under sufficient pressure to lift the plug from its seat. The compression chamber may be located either in the bearing surface of the valve or under the valve plug. For mechanical convenience, the latter arrangement is preferred. The conduits by which the lubricant is conveyed to the compression chamber may be variously located, either in the casing or in the body of the valve plug, but preferably in the bearing surface of the plug. These conduits or lubricating grooves are indicated at 52 and communicate at their upper ends with radial holes 53 which connect the grooves with the lower end of a pipe or lubricant reservoir 54 arranged within the valve stem 35. The lower ends of the grooves 52 communicate with the compression chamber 55 located between the bottom of the plug 14 and the base of the casing 12. The pipe 54 extends upwardly through the hollow valve stem 35 and terminates a short distance below the upper end of the latter, as indicated in Fig. 2. Screwed onto the upper end of the pipe 54 is an enlarged pipe 55 adapted to receive the screw 56, by turning which the lubricant in the pipe 54 is forced down into the lubricating grooves 52 and into the compression chamber 55. A set screw 57 holds the pipe 55 in place. By means of the screw 56 the lubricant in the pipe 54 and the compression chamber 55 may be put under sufficient pressure to lift the valve plug from its seat. This mode of operation is set forth in my Reissue Patent No. 14,516, reissued August 27, 1918. By turning the screw 56 when the handle 39 is

manipulated, the bearing surface of the valve may be kept lubricated and thereby prevent the likelihood of the plug becoming stuck or "frozen" in its seat. Moreover the 5 lubricant forms an effective seal and also prevents dirt and foreign substances from lodging in the seat and causing the valve to leak.

Having thus described the invention 10 what I claim to be new is:

1. A valve for tank cars and the like comprising a casing located in the bottom of the tank, a plug seated in the casing, a pipe extending from the plug upwardly through 15 the tank for containing lubricant, channels in the bearing surface of the plug connected with the pipe, means for forcing the lubricant from the pipe into the channels, a hollow stem enclosing the pipe and extending 20 from the plug upwardly through the tank, and a loose connection between the lower end of the stem and the upper end of the plug.
2. A valve for tank cars and the like comprising a casing located in the bottom of the tank, a plug seated in the casing, a hollow stem extending from the plug upwardly into the dome at the top of the tank, cooperating means on the bottom of the valve 25 stem and the top of the plug making a loose joint between them, a handle connected with the stem for manipulating the plug, a reservoir for lubricant consisting of a pipe located within the valve stem, lubricating 30 channels in the bearing surface of the plug connected with the pipe, a chamber in the casing under the plug, and means for forcing the lubricant through the channels and into the chamber to thereby lift the plug 35 from its seat.
3. A valve for tank cars and the like comprising a casing located in the bottom of the tank, a plug seated in the casing, a hollow valve stem connected with the plug and ex- 40 tending upwardly into the dome at the top 45 of the tank, a handle for manipulating the plug, a pipe located within the valve stem, lubricating channels in the bearing surface of the plug connected with the pipe and means for forcing the lubricant in the pipe 50 into the lubricating channels.
4. A valve for tank cars and the like comprising a casing located in the bottom of the tank, a plug seated in the casing, a flexible diaphragm for yieldingly holding the plug 55 in place, a hollow valve stem extending from the plug into the dome of the tank for turning the plug, a pipe located in the hollow valve stem, adapted to contain lubricant, lubricating channels in the bearing surface 60 of the plug and communicating with the pipe and means for forcing the lubricant into the lubricating channels.
5. A valve for tank cars and the like comprising a casing having a passageway therethrough with an inlet opening into the interior of the tank and substantially flush with the inside surface of the bottom of the tank and an outlet discharging through the bottom of the tank, a plug having a solid bottom seated in the casing and having a hole 70 adapted to register with the inlet opening, a plate adapted to be secured to the underside of the tank for supporting the valve casing within the tank, and a drain pipe 75 secured to the underside of the plate.
6. A valve for tank cars and the like comprising a casing having an elbow-shaped passageway therethrough, the inlet of the passageway being substantially flush with the inside surface of the bottom of the tank, and the outlet of the passageway discharging through the bottom of the tank, a plug seated in the casing and having a hole 80 adapted to register with the inlet opening, and means for supporting the valve casing in place in the bottom of the tank.

SVEN JOHAN NORDSTROM.
